Letters Patent

The Schedule referred to in these Letters Patent and making part of the same containing in the words of the said Joel Rathbone himself of his improvement in the fewy haup or flat Cook Stove.

Specification of improvement made in the fewy haup or flat Cook Stove by Joel Rathbone Albany N.Y.

Whereas inconvenience has arisen in the use of said Stove on account of the waste of heat the burning rate of the quard or front oven plate and the unequal distribution of heat through the oven. Wherefore certain improvements have been introduced which consist:

1st In recutting by a curve line or sweep so much of the front face plate as lies below the middle in such manner as to bring the face thereof more or less under the fire or bottom of the kettle - and 2nd In opening on the back side between the furnace and the oven, and between the flue that passes over and the flue that passes under the oven a horizontal passage for the air to circulate through. For further information reference may be had to the drawings and explanations connected herewith - What I claim as my invention of improvement is first, the introduction into the fewy haup or flat Cook Stove of the aforesaid horizontal flue between the furnace and the oven and second the combining therewith in said Stove the recut or sunk front plate in manner aforesaid together with the uses to which the same has been or may hereafter be applied.
